CLAIM

The ornamental design for an all-terrain vehicle body as shown and described.

DESCRIPTION

FIG. 1 is a perspective view taken from a front, left side of an all-terrain vehicle body according to our design;

FIG. 2 is a perspective view taken from a front, right side thereof;

FIG. 3 is a perspective view taken from a rear, right side thereof;

FIG. 4 is a perspective view taken from a rear, left side thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

Throughout the Figures, where shown, the dashed lines illustrate features that do not form part of the claimed design.

1 Claim, 10 Drawing Sheets
